UNITED STATES PATENT OFFICE.

GEORGE G. HALL, OF LOS ANGELES, CALIFORNIA.

SHOE-BRUSHING MACHINE.

1,275,674.

Specification of Letters Patent. Patented Aug. 13, 1918.

Application filed January 3, 1918. Serial No. 210,118.

To all whom it may concern:

Be it known that I, GEORGE G. HALL, a citizen of the United States, residing at Los Angeles, in the county of Los Angeles and State of California, have invented certain new and useful Improvements in Shoe-Brushing Machines, of which the following is a specification.

My invention relates to machines for brushing, cleaning or polishing, boots and shoes.

An important object of the invention is to provide a machine of the above mentioned character, which is adapted to operate in a highly expeditious and efficient manner.

A further object of the invention is to provide a machine of the above mentioned character, having means to clean, apply a liquid polish to, and polish the shoes.

Other objects and advantages of the invention will be apparent during the course of the following description.

In the accompanying drawings forming a part of this specification and in which like numerals are employed to designate like parts throughout the same,

Figure 1 is a plan view of a machine embodying my invention,

Fig. 2 is a longitudinal sectional view taken on line 2—2 of Fig. 1,

Fig. 3 is a transverse sectional view taken on line 3—3 of Fig. 1,

Fig. 4 is a section similar to Fig. 3, showing the sponge or dauber in the elevated position, with parts broken away, and,

Fig. 5 is a transverse sectional view taken on line 5—5 of Fig. 2.

In the drawings, wherein for the purpose of illustration is shown a preferred embodiment of my invention, the numeral 10 designates a casing, having a longitudinal section 11 and a transverse section 12.

Arranged in the rear end of the longitudinal casing section 11 is a vertical driving shaft 13, journaled in bearings 14; secured to the top and bottom of the casing section 11. Rigidly secured to the vertical shaft 13 for rotation therewith is a pair of spaced horizontal sprocket wheels 15, engaged by a pair of horizontal sprocket chains 16, extending forwardly for engagement with a pair of horizontal sprocket wheels 17, which are rotatable upon a stub shaft 18. This stub shaft is rigidly secured

to a foot support or rest 19 attached to supports or posts 20 in turn secured to the bottom of the casing section 11. The casing section 11 has an opening 19' disposed near and above the foot rest 19.

The numeral 21 designates a dauber brush, 22 a stiff cleaning brush to remove mud, dirt or the like from the shoes, 23 a buffing brush, and 24 a polisher brush. Each of these brushes includes a back 25 connected with the upper ends of suitably stiff flexible leaf-springs 26, which are substantially vertically arranged, and are connected with the sprocket chains 16, as shown at 27. These brushes are vertically arranged, or stood on edge in a vertical plane, whereby their contacting faces operate in vertical planes. The flexibility or yielding action of the springs 26 is sufficient to enable the brushes to travel with the sprocket chains about the several sprocket wheels.

Arranged within one end of the transverse casing section 12 is a horizontal transverse driving shaft 28, which may constitute the armature shaft of a motor 29, or may be geared thereto by any suitable means. The opposite end of the shaft 28 is journaled in a bearing 30. Rigidly mounted upon the shaft 28 is a pair of spaced vertical sprocket wheels 31, engaged by a pair of spaced sprocket chains 32, also engaging vertical sprocket wheels 33, rotatable upon stub shafts 34. These stub shafts are connected with the opposite end of the casing section 12, as shown at 35.

The numeral 36 designates a dauber brush, 37 a polisher brush, 38 a buffing brush, and 39 a stiff cleaner brush. Each of these brushes includes a flexible back 40, extending transversely between the chains 32, and suitably attached to the same, as clearly illustrated in Fig. 1. The flexibility of the backs of these brushes enables the same to travel with their sprocket chains about the several sprocket wheels.

Means are provided to apply a liquid blacking to the dauber brush 21, including, as shown more clearly in Fig. 5, a liquid blacking holding receptacle 41, adapted for the reception therein of a sponge or absorbing element 42, secured to the end of a rod 43. This rod is pivoted at 44 to a stationary support 45 and is adapted to swing in a vertical plane transversely of the casing

section 11. The location of the rod 43 is clearly indicated in Fig. 1, as inwardly of and near the sprocket wheels 15. Rigidly secured to the rod or lever 43 near and 5 spaced from its pivot is a crank 46, projecting into the path of travel of a trip-cam 47, secured to the lower chain 16, and at a suitable position thereon, to contact with the crank 46, and elevate the rod 43, 10 when the dauber brush 21 is in a position to contact with the sponge 42. It is thus apparent that automatic means are provided to apply a liquid blacking to the dauber brush.

15 Automatic means are also provided to apply a liquid blacking to the dauber brush 36 of the transverse sprocket chains, comprising, as shown more clearly in Figs. 3 and 4, a liquid blacking holding receptacle 48, 20 adapted to receive therein a sponge 49 or other absorbent element, secured to a rod 50 pivoted at 51 to a stationary support 52. The rod 50 is adapted to swing in a vertical plane longitudinally of the casing section 12 and 25 is arranged between the sprocket wheel 33, as clearly indicated in Fig. 1. Rigidly secured to the rod 50 is a laterally extending cam-crank 53, disposed in the path of travel of a pin or extension 54, secured to one 30 sprocket chain 32. The pin 54 is so arranged with relation to the chain 32, that when the dauber brush 36 is in the position indicated in Fig. 4, the sponge 49 is automatically shifted to the upper position to 35 contact with this dauber brush. When the pin 54 disengages the crank-cam 53 the rod 50 automatically returns to the lower position aided by a spring 51'.

As more clearly shown in Figs. 1 and 2, 40 the longitudinal sprocket chains extend within or between the transverse sprocket chains, and it is therefore necessary that the two sets of sprocket chains be positively 45 geared together and timed in their operation, so that the brushes carried by the transverse sprocket chain will pass within the spaces between the brushes carried by the longitudinal sprocket chains. To accomplish this, the shaft 28 has a bevel gear 55, rigidly 50 secured thereto, engaging a bevel gear 56, rigidly secured to the shaft 57. This shaft is provided at its opposite end with a bevel gear 58 rigidly secured thereto, engaging a bevel gear 59, rigidly secured to a shaft 55 55 60, extending longitudinally within the casing section 11. At its rear end the shaft 60 has a bevel gear 61, rigidly secured thereto and engaging a bevel gear 62, rigidly secured to a rotatable vertical shaft 63. This 60 vertical shaft 63 has a sprocket wheel 64 rigidly secured to its upper end, engaged by a sprocket chain 65, engaging a sprocket wheel 66, which is rigidly secured to the upper end of the shaft 13.

The motor 29 is connected with wires 67 66 and 68, the wire 68 having a source of current 69 connected therein. Any suitable means may be employed to electrically connect the wires 67 and 68 for closing the circuit and I may provide coin control means 70 (not shown) of any well known or preferred construction. In the event that coin control means are provided suitable means will also be provided to automatically stop the operation of the machine after the endless chains 75 have made a complete revolution.

The operation of the machine is as follows: The operator places his foot through the opening 19' upon the foot rest 19, whereby the shoe assumes a position shown in Fig. 3. 80 It is thus apparent that the vertical brushes carried by the longitudinal sprocket chains are adapted to contact with the sides of the shoe, while the horizontal brushes contact with the upper portion of the forward end 85 of the shoe or the cap.

When the machine is started, the sprocket chains 16 travel in the direction of their arrow, while the sprocket chains 32 travel in the direction of the arrow disposed near 90 the same. The cleaner brushes first remove the mud, dirt, or the like from the shoe. The liquid blacking is automatically supplied to the dauber brushes, and these dauber brushes in turn apply the same to the shoe. The 95 other brushes act then upon the shoe in a manner to polish or clean the same, as is obvious.

It is to be understood that the form of my invention herewith shown and described is 10 to be taken as a preferred example of the same, and that various changes in the shape, size, and arrangement of parts may be resorted to without departing from the spirit 10 of the invention or the scope of the subjoined claim.

Having thus described my invention, I claim:

A machine comprising, a substantially horizontal foot support, a pair of horizontal 11 sprocket wheels arranged beneath the foot support and rotatably connected therewith, a vertical spindle disposed at a substantial distance from the foot support, a second 11 pair of horizontal sprocket wheels secured to the vertical spindle, a pair of sprocket chains engaging the horizontal sprocket wheels and having their edges arranged in horizontal planes, said pair of sprocket chains traveling longitudinally about the foot support, a plurality of brushes arranged on edge in vertical planes, means connecting the brushes with the pair of sprocket chains, pairs of vertical sprocket wheels arranged upon opposite sides of the foot support, a pair of sprocket chains engaging the vertical sprocket wheels and having portions 12 thereof arranged upon opposite sides of the

foot support, the last named sprocket chains having their edges arranged in vertical planes, a plurality of horizontal brushes spanning the space between the last named 5 sprocket chains and connected therewith, and means to drive one pair of vertical sprocket wheels and the vertical spindle in unison.

In testimony whereof I affix my signature in presence of two witnesses.

GEORGE G. HALL.
